UNITED STATES PATENT OFFICE

2,598,456

BOBBY PIN

Burton K. Snyder, Chicago, Ill., assignor to Gaylord Products, Incorporated, Chicago, Ill., a corporation of Delaware

Application January 21, 1949, Serial No. 71,787

3 Claims. (Cl. 132—50)

1

This invention relates to hair fasteners and is more particularly concerned with the provision of a hair fastener of the bobby pin type comprising a piece of resilient wire bent intermediate its ends to form opposing hair clamping legs normally disposed in contacting engagement by means of a connecting loop portion.

The present invention contemplates the provision of a bobby pin construction in which the opposing legs are placed under a relatively high initial tension or clamping force to prevent accidental displacement of the bobby pin from a relatively small lock of hair or from a display card upon which the bobby pins are mounted for distribution and sale. In the manufacture of bobby pins, a piece of resilient wire is bent intermediate its ends to form opposing legs and a connecting loop portion and it is well known in this art that such an operation places the metal along the inner face of the loop portion under compression and places the metal on the outer face of the loop portion under tension. To cause the legs of the bobby pin to exert a higher initial clamping force, the present invention contemplates the provision of a shot peening operation on the outer surface of the loop portion to thereby cause the metal on the outer surface to be placed under compression. By shot peening the outer surface of the connecting loop portion of the bobby pin, it has been found possible to open the legs of the bobby pin to a greater width without exceeding the elastic limits of the material. It will be appreciated that a bobby pin loses its usefulness in clamping hair in position when the elastic limits of the material has been exceeded to cause the legs of the bobby pin to be set to an open spaced-apart position.

In the preferred form of construction, the bobby pins are formed from round, oval or half-round wire bent intermediate its ends to form opposing legs of gradually increasing width and decreasing thickness, with one of the legs crimped transversely at spaced intervals and throughout the major portion of its length. In this form of construction, the bending strength of the legs at various points throughout their length is proportional to the leverage between the various points and their connected ends, thus permitting a more uniform spread of the legs throughout their length without exceeding the elastic limits of the various sections. By shot peening the outer surface of the connecting loop portion and the portions of the legs adjacent thereto, the legs of the bobby pin may be spread apart to a greater width than has heretofore been pos-

2

sible without exceeding the elastic limit of the material. This invention embodies other novel features, details of construction and arrangement of parts which are hereinafter set forth in the specification and claims and illustrated in the accompanying drawings, wherein:

Fig. 1 is a top plan view showing a bobby pin embodying features of this invention.

Fig. 2 is a side elevational view of same.

Fig. 3 is a bottom plan view of same.

Fig. 4 is a graph illustrating the opening of unpeened bobby pins subjected to unit loads.

Fig. 5 is a graph illustrating the opening of peened, heat-treated bobby pins under unit load.

Fig. 6 is a graph illustrating the opening of peened, heat-treated, black japanned bobby pins under unit load.

Fig. 7 is a graph illustrating the initial grip of unpeened bobby pins, peened bobby pins, and peened black japanned bobby pins.

Referring now to the drawings for a better understanding of this invention, the bobby pin is shown as preferably comprising a length of resilient wire bent intermediate its ends to form a loop portion 6 and a pair of depending legs 7 and 8 of gradually increasing width and decreasing thickness from the loop portion to their free ends. It is contemplated that the bobby pin may be formed from round, oval or half-round resilient steel wire. The outer leg 7 is formed throughout the greater portion of its length with a plurality of inwardly converging crimps having their bases 9 normally disposed in contact with the opposing leg 8. A relatively large hair receiving pocket 11 is formed at the inner end of the bobby pin and is defined by the leg 8, the uncrimped portion 12 of the crimped leg 7, and the connecting loop portion 6.

When a bobby pin has been formed in the manner illustrated and described, the metal defining the inner surface of the loop end of the bobby pin is under compression, while the metal defining the outer surface 14 of the loop end is under tension. To increase the initial grip of the opposing legs 7 and 8 and also to permit the legs to be spread to a wide open position without exceeding the elastic limit of the material, the outer surface of the bobby pin adjacent the loop end 6 is shot peened to place the metal under compression. The apparatus for accomplishing the shot peening operation may be of any suitable type, well known to those skilled in the art, in which relatively small steel shot are directed against the outer surface of the loop end of the bobby pin at various intensi-

ties which, for example, may be of from .002 arc height to .012 arc height depending upon the carbon content of the steel wire and the physical properties desired to be imparted to the bobby pin. As illustrated in Fig. 5, groups of bobby pins were shot peened at various intensities ranging from .002 arc height to .012 arc height in order to determine which intensities were most desirable. In the chart it will be noted that bobby pins shot peened to an arc height intensity of .012 offered greater resistance to initial load deflection than bobby pins shot peened to an arc height of .002. However, the tests indicated that the deflection or spread of the bobby pin legs was substantially equal at the maximum unit load or the point at which the material reached the end of its elastic limit.

In making the tests of peened bobby pins and unpeened bobby pins it was found that 60% of the unpeened pins were sprung beyond their elastic limits under the unit load "E," while only 26% of the peened pins were sprung beyond their elastic limits under the unit load indicated at "E."

Fig. 7 in the drawings graphically illustrates the units of initial grip of unpeened bobby pins and shot peened bobby pins and it will be noted that the initial grip of peened bobby pins greatly exceeds the initial grip of unpeened bobby pins. It was further learned that the overall stiffness and holding power of the shot peened bobby pins exceeded that of the unpeened pins by 18½%.

It is a common practice in this industry to japan pins after heat-treatment to provide the pins with a relatively hard, smooth, moisture-resistant surface. As graphically illustrated in Fig. 4, the japanning operation appears to normalize or anneal the metal as japanned bobby pins have greater deflection under unit load than unjapanned bobby pins.

Fig. 6 in the drawings graphically illustrates the deflection under unit load of bobby pins which have been peened after heat-treatment and then black japanned after peening. It will be noted that these bobby pins were subjected to a relatively greater unit load "F" and greater deflection "10" without exceeding the elastic limit of the metal. A comparison of the tests between japanned pins and unjapanned pins is graphically illustrated in Figs. 6 and 5, respectively. In carrying out the tests of bobby pins it was found that only 3.3% of the pins were sprung beyond their elastic limits under the unit load indicated at "E," whereas 60% of the unpeened, unjapanned pins opened at "E" and 26% of the peened, unjapanned pins opened at "E."

In the manufacture of bobby pins of the type illustrated and described, the pins are first formed on a conventional forming machine and then heat-treated to enhance the physical properties of the metal. The loop end of the bobby pin is then shot peened along its outer surface to place the metal along the outer surface under compression. The heat-treated, shot peened pin is then japanned, if desired. The results of numerous tests indicate that heat-treated, shot peened pins may be opened to a greater degree than heat-treated pins which have not been shot peened, and that heat-treated, shot peened, japanned pins may be opened to a greater degree than heat-treated, shot peened pins without exceeding the elastic limit of the metal. In subjecting the several types of pins to a predetermined unit load,

it was found that the elastic limit of the metal was exceeded on 60% of the unpeened unjapanned pins, the elastic limit of the metal was exceeded on 26% of the peened unjapanned pins, and the elastic limit of the metal was exceeded on only 3.3% of the peened japanned pins. The tests further indicate that heat-treated, shot peened pins have a higher initial grip than pins which are not shot peened.

In summarizing the advantages of the shot peening operation, shot peening the loop ends of bobby pins definitely improves the initial tension, overall stiffness, and gripping qualities, and at the same time permits the legs to be spread farther apart without exceeding the elastic limit of the metal. The tests indicate that shot peening the pins at increased arc height intensities further enhances the physical properties of the pins, that shot peened pins have an initial grip 25% greater than unpeened pins, and that the overall stiffness and holding power of shot peened pins exceeds that of the unpeened pins by 18%.

While this invention has been shown in but one form, it is obvious to those skilled in the art that it is not so limited but is susceptible of various changes and modifications without departing from the spirit and scope of the claimed invention.

I claim as my invention:

1. A bobby pin formed of resilient heat-treated metal, comprising a pair of opposing legs, and a loop connection normally urging said legs into contacting engagement, the surface metal along the outer surface of said loop connection and along the outer surface of adjacent portions of said legs being locally densified and relieved of residual tensile stresses.

2. A bobby pin formed of resilient heat-treated metal, comprising a pair of opposing legs, and a loop connection normally urging said legs into contacting engagement, the surface metal along the outer surface of said loop connection and along the outer surface of adjacent portions of said legs being locally densified and relieved of residual tensile stresses, said bobby pins being provided with a japanned finish.

3. A bobby pin formed of resilient metal, comprising a pair of opposing legs, and a loop connection normally urging said legs into contacting engagement, the surface of the metal along the outer portion of said loop connection and along the outer surface of adjacent portions of said legs being densified and relieved of tensile stresses occasioned by forming the loop, said bobby pins being provided with a japanned finish.

BURTON K. SNYDER.
